LOCKNUT

Paul D. Myers, Fullerton, Calif., assignor to Microdot,
Inc., South Pasadena, Calif.

Filed June 23, 1969, Ser. No. 17,829

Term of patent 14 years

Int. Cl. D8—04

U.S. Cl. D8—273

FIG. 4.

FIG. 5.

FIG. 1 is a top plan view of a locknut, showing my new design.

FIG. 2 is an elevational view thereof, viewed in the direction indicated by the arrows 2—2 of FIG. 1.

FIG. 3 is an elevational view thereof, viewed in the direction indicated by the arrows 3—3 of FIG. 1.

FIG. 4 is a bottom plan view of the locknut of FIG. 1.

FIG. 5 is a perspective view of the locknut of FIG. 1.

I claim:

The ornamental design for a locknut, substantially as shown.
